UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 24,810, dated October 29, 1895.

Application filed September 3, 1895. Serial No. 561,378. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Fabric, of which the following is a specification, reference being had to the accompanying drawing.

10 The leading feature of my design is a center panel, representing scrolls, branches, leaves, and flowers surrounded by a representation of four peacocks, the corners being ornamented by floral figures, the whole surrounded by an

15 ornamental border.

The drawing shows only one half of the design. The half not shown is identically like the half that is shown.

Having as above fully described my invention, what I claim as new, and desire to secure 20 by Letters Patent, is—

The design for a woven fabric, as shown and described.

W. T. SMITH.
